UNITED STATES PATENT OFFICE.

HENRY G. VOIGHT, OF NEW BRITAIN, CONNECTICUT, ASSIGNOR TO THE RUSSELL & ERWIN MANUFACTURING COMPANY, OF SAME PLACE.

DESIGN FOR A KEEPER FOR LOCKS AND LATCHES.

SPECIFICATION forming part of Design No. 31,929, dated December 5, 1899.

Application filed November 7, 1899. Serial No. 736,192. Term of patent 7 years.

To all whom it may concern:

Be it known that I, HENRY G. VOIGHT, a citizen of the United States, residing in New Britain, in the county of Hartford and State of Connecticut, have invented and produced a new and original Design for a Keeper for Locks and Latches, of which the following is a specification, reference being had to the accompanying drawing, in which the figure is a perspective view of a keeper for locks and latches, showing my new design.

As shown in the drawing, the keeper is in the shape of a flat plate with mainly parallel straight vertical side edges 2 2 and with rounded ends 3 3. On one of the side edges, near the middle of its length, there projects a rectangular wing 4, as shown. On the opposite side edge there is a series of pointed projections 5, at regular distances apart, the upper and lower projections being at the junction

of one vertical side edge 2 and rounded ends 3 3. Near each end of the keeper there is a round hole 6, concentric with the rounded ends 3 3 and in transverse alignment with the respective upper and lower pointed projections 5. In the body of the keeper, opposite the wing 4, is a rectangular hole 7, and below said hole is a longer rectangular hole 8, all combined and arranged, as shown, to produce the complete design. 25 30

Having now described my invention, what I claim as new, and desire to secure by Letters Patent, is—

The design for a keeper for locks and latches, as herein shown and described.

HENRY G. VOIGHT.
